INK MARKING INSTRUMENT OR THE LIKE

Walter J. De Groft, Glen Ellyn, Ill., assignor to Sanford Research Company, Bellwood, Ill., a corporation of Illinois

Filed Nov. 29, 1963, Ser. No. 77,602

Term of patent 14 years

(Cl. D74—17)

FIG. 1 is a perspective view of an ink marking instrument or the like embodying my design;

FIG. 2 is a side elevational view of the ink marking instrument or the like shown in FIG. 1;

FIG. 3 is another side elevational view of the ink marking instrument or the like shown in FIG. 1 rotated 90° from the position shown in FIG. 2; and

FIG. 4 is a plan view of the ink marking instrument or the like shown in FIG. 1.

The dominant features of my design shown herein reside in the cap member.

I claim:

The ornamental design for an ink marking instrument or the like, as shown and described.
